Primary Examiner — Susan E Krakower*Assistant Examiner* — Michelle M Reeves(74) *Attorney, Agent, or Firm* — Fross, Zelnick, Lehrman & Zissu, P.C.; Charles T. J. Weigell, Esq.(57) **CLAIM**

The ornamental design for a stool as shown and described.

DESCRIPTION

FIG. 1 is a front perspective view of a stool showing our new design;

FIG. 2 is a front view thereof;

FIG. 3 is a top view thereof;

FIG. 4 is a right side view thereof, with the left side being a mirror image; and,

FIG. 5 is a bottom view thereof.

The broken lines shown in the drawings show portions of the stool that form no part of the claimed design.
